UNITED STATES PATENT OFFICE.

WILLIAM EARL UNDERWOOD, OF GAINESVILLE, TEXAS.

DESIGN FOR A SPUR-BODY.

SPECIFICATION forming part of Design No. 35,696, dated February 4, 1902.

Application filed November 12, 1900. Serial No. 36,301. Term of patent 7 years.

To all whom it may concern:

Be it known that I, WILLIAM EARL UNDERWOOD, a citizen of the United States, residing at Gainesville, in the county of Cooke and State of Texas, have invented and produced 5 a new and original Design for a Spur-Body; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 is a side elevation of a spur-body of my new design, and Fig. 2 is a plan of the same.

As shown in the drawings, the leading or material feature of my design consists in a 20 spur-body having its strap-buttons at the extremities of fixed arms extending upward

from the heel-band at substantially right angles in side elevation.

In the drawings, *a* indicates the rowel-arm, and *b* the heel-band, U-shaped in plan to fit 25 the wearer's heel and in side elevation having the horizontally-disposed portion *b'*, with fixed arms or upright portions *b²* extending from the ends of said horizontal part *b'* upward at substantially right angles thereto. 30 Strap-buttons *c* are at the extremities of said upright arms or portion.

What I claim as new is—

The design for a spur-body as herein shown and described.

In testimony that I claim the foregoing I have hereunto set my hand this 5th day of November, 1900.

WILLIAM EARL UNDERWOOD.

Witnesses:

CHARLES KASSEL,
W. O. DAVIS.
